CONTAINER

Louis W. Sutherland, Kalamazoo, Mich., assignor to Sutherland Paper Company, Kalamazoo, Mich.

Application April 6, 1932. Serial No. 603,479

9 Claims. (Cl. 229—45)

The main objects of this invention are:

First, to provide a container which is well adapted for food products which may be very quickly closed and the closure or cover securely

5 retained, and at the same time one which may be very quickly and easily opened without the use of implements.

Second, to provide a container having these advantages which is economical in material and 10 very easily set up by hand or with the aid of machines of standard types.

Third, to provide a container having these advantages which is very strong and rigid in construction, even when made of comparatively light 15 material, and one in which the cover or closure is securely retained.

Objects pertaining to details and economies of 20 my invention will appear from the description to follow. The invention is defined and pointed out in the claims.

25 A structure which is a satisfactory embodiment of my invention is illustrated in the accompanying drawing, in which:

Fig. 1 is a perspective view of a container embodying the invention.

25 Fig. 2 is a perspective view of the container partly opened, showing the first step in removing the closure.

Fig. 3 is a perspective view of the closure.

30 Fig. 4 is a fragmentary vertical section taken on line 4—4 of Fig. 5.

Fig. 5 is a fragmentary vertical section taken on line 5—5 of Fig. 4.

Fig. 6 is a fragmentary vertical section taken 35 on line 6—6 of Fig. 4.

Fig. 7 is a top plan view of the container cut out before folding.

Referring to the drawing, 1 indicates a container embodying the invention. In the embodiment illustrated the container is formed of a blank comprising a bottom portion 2 having opposed side walls 3 extending from opposite edges thereof and joined thereto along the score lines indicated at 6. Side wall flaps 9 project 45 from the other edges of the bottom 2 and are joined thereto along the score lines 10.

The side wall portions 3 have outer and inner overlapping side wall extensions 4 and 5 respectively extending from their lateral edges and 50 joined thereto along the score lines 7 and 8. The side walls 3 and the inner side wall extensions 5 have inwardly projecting beads 12 spaced from their upper edges and providing ledges or supporting shoulders for the cover or closure 14.

55 The inner side wall extensions 5 have spaced slits extending from their upper edges to the beads providing tongues 13 adapted to be folded inwardly to a horizontal position as shown in Fig. 4 to support the cover. The outer side wall extensions 4 have finger notches 20 therein alined

with the tongues 13 to facilitate the engagement of these tongues to swing them down to cover-supporting position when the cover is to be inserted.

The cover 14 is provided with flanges 15 on its edges, the cover being scored at the bases of the flanges as at 16 to facilitate the inserting of the cover or the bending of the flanges at the proper point. At the base of an exposed pair of flanges the cover is provided with slits 21 adapted to receive the tongues 19 on the edges of the cover-retaining flaps 17. These cover-retaining flaps 17 extend from the upper edges of the side walls 3, the scores 18 at the bases of the flaps facilitating the folding thereof over the cover flanges as shown in Figs. 1, 2, 4 and 5, thereby effectively locking the cover in place.

The cover, being supported by the beads and cover supports 13, is not easily pushed inward, and is properly positioned to receive the retaining flaps 17 so that in assembling the cover it is only necessary to insert the cover upon the supports and swing the flaps 17 inwardly, pressing them against the adjacent cover flanges which causes the tongues or tabs 19 to snap into the slits, effectively securing the cover.

When it is desired to open the container the upper edges of the side walls 3, or the side walls having the cover retaining flaps therein, are grasped and forcibly pulled outwardly, breaking down the container at the corner as shown in Fig. 2 so that the cover can be readily lifted out. The finger notches 20 facilitate the grasping of the cover after it has been released as shown in Fig. 2 as well as constituting means for facilitating the adjustment of the tongues 13.

The container is strong and rigid by virtue of its construction, and it is impossible for the cover to fall off or even be forced off without going through the cover-removing operations described. With this construction the container may be packed upside down without the possibility of the cover being released. The device is also simple and compact in its parts and economical to manufacture.

I have illustrated and described my improvements in an embodiment which I have found very practical. I have not attempted to illustrate or describe other embodiments or adaptations as it is believed this disclosure will enable those skilled in the art to embody or adapt my improvements as may be desired.

Having thus described my invention what I claim as new and desire to secure by Letters Patent is:

1. A container formed of an integral blank comprising a bottom portion and opposed side wall portions extending from opposite edges of the bottom portion and side wall flaps extending from the other opposite edges of the bottom

- portion, said side wall portions having laterally extending overlapping side wall extensions between which said side wall flaps are disposed, said side wall portions having longitudinally extending cover-engaging flaps provided with tongues on their edges, said side wall portions and the inner pair of side wall extensions having score-like inwardly projecting beads spaced from their upper edges to provide cover supports, the inner pair of side wall extensions having slits extending from their upper edges to said beads to provide cover-supporting tongues, the outer pair of side wall extensions having finger notches alined with such tongues, and a cover disposed within said container to rest on said cover-supporting tongues and beads and provided with side flanges, opposed side flanges having slots at the bases thereof receiving the tongues on said cover-retaining flaps. 30
5. A container comprising opposed side walls having laterally extending overlapping side wall extensions, said side walls having longitudinally extending cover-engaging flaps provided with tongues on their edges, said side walls and the inner pair of side wall extensions having score-like inwardly projecting beads spaced from their upper edges to provide cover supports, the inner pair of side wall extensions having slits extending from their upper edges to said beads to provide cover-supporting tongues, the outer pair of side wall extensions having finger notches alined with such tongues, and a cover disposed within said container to rest on said cover-supporting tongues and beads provided with side flanges, opposed side flanges having slots at the bases thereof receiving the tongues on said cover-retaining flaps. 85
6. A container comprising opposed side walls 100 having laterally extending overlapping side wall extensions, said side walls having longitudinally extending cover-engaging flaps provided with tongues on their edges, the inner pair of side wall extensions having slits extending from their upper edges to provide cover-supporting tongues, the outer pair of side wall extensions having finger notches alined with such tongues, and a cover disposed within said container to rest on said cover-supporting tongues and provided with side 105 flanges, opposed side flanges having slots at the bases thereof receiving the tongues on said cover-retaining flaps. 90
7. A container having opposed side walls 110 provided with cover-engaging flaps having tongues 115 on their edges, the other pair of side walls having inner flaps provided with inwardly projecting cover-supporting tongues, and a cover disposed within said container to rest on said cover-supporting tongues and provided with side flanges 120 over which the said cover-retaining flaps are folded and with slits at the bases of said flanges to receive said tongues on said cover-retaining flaps. 125
8. A container comprising opposed side walls 125 having laterally extending overlapping side wall extensions, the inner pair of side wall extensions having slits extending from their upper edges to provide cover-supporting tongues, the outer pair of side wall extensions having finger notches 130 alined with the openings left by such tongues, and a cover disposed within said container to rest on said cover-supporting tongues and provided with side flanges covering said finger notches. 135
9. A container comprising opposed side walls 140 having laterally extending overlapping side wall extensions, said side walls having longitudinally extending cover-engaging flaps, the inner pair of side wall extensions having cover-supporting means, the side wall extensions having registering recesses providing finger notches, and a cover disposed within said container to rest on said cover-supporting means and provided with upwardly extending side flanges in operative relation with said finger notches. 145
